BRAKE

Walter H. Delahaye, Ottawa, Ontario, Canada,
assignor to Bendix Brake Company, South
Bend, Ind.

Application December 2, 1929. Serial No. 410,937

7 Claims. (Cl. 188—78)

This invention relates to automobile brakes and has for its object to provide a novel brake having a servo action developed by a shoe which is either directly connected to one of the main shoes or is integral therewith.

A novel feature of the device also resides in the brake-applying means which provides a simple and effective means for transmitting a servo initiated force to the main shoe.

10 The invention consists in the combination, construction and arrangement of parts herein-after described and more particularly pointed out in the appended claims.

A number of embodiments of the invention 15 are illustrated by way of example, in the accompanying drawing in which:

Figure 1 is an elevation partially in section on line 1—1 of Figure 2 of a portion of one 20 form of the invention showing applying means which may conveniently be used with all modifications of the servo shoe disclosed herein.

Figure 2 is a detail of the applying means shown in Figure 1.

Figures 3 and 4 show modifications in the 25 construction of the resilient connection between one of the main shoes and the servo shoe attached thereto.

Figure 5 and 6 show details of the spring support used in the construction shown in Figure 4. 30 1 indicates a brake drum in which a pair of shoes 2 and 3 are mounted in the usual manner on a fixed pivot 4. The free end of the brake shoe 2 is provided with a flat surface 5 considerably greater in area than is usually employed in 35 ordinary cam brakes. This surface is intended to co-operate with the applying means carried on the other shoe 3. These means are carried on and operated by a rockshaft 6 pivoted in the free end of the shoe 3. This shaft 6 carries a 40 cam 7, which is fixed thereto in the customary manner and also a depending lever 8. The free end of the shoe 3 may be formed with a pair of spaced ears 9, which may be constructed by separating the two parts of the rib of the shoe, 45 the shoe being formed by a pair of angles placed back to back. Between these ears may be fitted the bifurcated ends 10 of the lever 8, these bifurcated ends providing a free space on the shaft 6 for the mounting of the cam 7. The lever 8 50 is adapted to pivot on a stop 11 on the operation of the servo part of the shoe 3. The portion of the shoe 3, designated by the numeral 12, is constructed to act as a servo shoe and therefore must have a limited freedom of movement in a 55 circumferential direction. In Figure 1 this is

provided for by constructing a resilient loop 13 in the shoe. The web of the shoe is cut off and the remaining flat flange portions are formed into the loop 13 to which a certain amount of resiliency must be imparted. If the nature of 60 the material from which the shoe is made permits tempering this may be done. Another expedient in the shape of a spring insert 14 may be resorted to.

In the modification shown in Figure 3, the 65 servo section is separate from the main part of the shoe 3. The central webs of the portion 12 are separated to provide spaced parallel parts 15 and the adjacent portions 16 of the web of the shoe 3 are similarly spread and are adapted to 70 receive the parts 15 between them. Any means may be used to hold these parts in sliding assembled relation. This detail has not been shown in the drawing as any well-known construction may be employed. The parts when so 75 assembled form a pocket to receive a compression spring 17 which acts to keep the parts in extended position.

In the construction shown in Figure 4, the 80 webs of the shoe 3 and the servo portion 12 are only separated sufficiently to permit their being overlapped in superimposed relation and in such a position that the large openings 18 provided therein are normally in register. In the openings 85 a spring 19 is mounted by means of spring seats 20 which have a slotted end 21 to receive the material of the webs to center the seats and hold the spring in its operative position.

The operation of the brake, through apparent 90 from the above description, will be briefly reviewed. When the shaft 6 is turned in the operation of applying the shoes by means of the usual lever 22 and brake rod 23, the shoes are expanded and engage the drum 1 throughout 95 their length. If the drum is rotating in a clockwise direction the servo portion 12 will be urged in a like direction and can do so by the resilient mounting which connects it to the remainder of the shoe, 3. This movement will carry the shaft 6 with it, clearance 24 being provided in the opening in the axle flange to permit this. As the shaft moves it carries the lever 8 against the stop 11 and therefore the free end of this lever moves in the opposite direction and exerts an expanding force on the surface 5 of the 100 shoe 2.

Various modifications of the above constructions may be made and it is the intention to cover all such modifications as may rightly fall 110 within the scope of the appended claims.

What I claim is:

1. In a servo brake, a pair of pivoted shoes, one shoe having a main portion and a servo portion, said portions being resiliently connected, 5 said portions having a web composed of two individual webs lying back to back, said individual webs being spaced at the adjacent ends of the portions to present overlapping faces adapted to slide on one another, a spring opening formed in the separated overlapping sections of the web, and a spring in said opening. 10
2. In a servo brake, a pair of pivoted shoes, one of said shoes having a servo section resiliently attached thereto at its free end, a cam shaft mounted in the free end of the servo shoe, a cam fixed on said shaft and a lever free on the shaft, a stop adapted to be engaged by the lever and a surface on the free end of the other pivoted shoe to be engaged by the free end of 15 the lever. 20
3. In a servo brake as set forth in claim 2, said stop being positioned between the cam shaft and the point of engagement of the lever and the free end of the other shoe, and in advance 25 of the lever in regard to the direction of rotation in which the desired servo action is to take place. 30
4. In a servo brake as set forth in claim 2, said servo shoe having spaced ears in which the

camshaft is journalled, said lever having perforated bifurcations loosely journalled on the shaft, said cam being fixed to said shaft and located between the bifurcated ends of the lever. 80

5. In a brake shoe, a main section adapted to be mounted on a fixed pivot and a servo section resiliently connected thereto, both of said sections being adapted to engage the same zone of the surface of a cooperating brake drum, said connection presenting slidably engaging parts on the respective sections and resilient means to maintain the sections in an extended position. 85

6. In a brake shoe a main section adapted to be mounted on a fixed pivot and a servo section resiliently connected thereto, both of said sections being adapted to engage the same zone of the surface of a cooperating brake drum, said sections being each formed with a flange carrying a friction facing and a reinforcing web, said webs being provided at their adjacent ends with separated portions slidably engaging the corresponding portions of the web of the other section in combination with a spring seated between the engaging web portion. 90

7. A brake shoe comprising a member formed in two parts including a flange bent to provide a flexible connection between the parts. 95
